UNITED STATES PATENT OFFICE.

HENRY C. KRIETE, OF CHICAGO, AND WILLIAM GILLIES, OF SOUTH CHICAGO, ILLINOIS.

MACHINE FOR STAMPING RAILS.

SPECIFICATION forming part of Letters Patent No. 337,837, dated March 16, 1886.

Application filed October 27, 1885. Serial No. 181,051. (No model.)

To all whom it may concern:

Be it known that we, HENRY C. KRIETE and WILLIAM GILLIES, citizens of the United States of America, the former residing at Chicago and the latter at South Chicago, in the county of Cook and State of Illinois, have invented certain new and useful Improvements in Rail-Stamping Machines, of which the following is a specification, reference being had 10 therein to the accompanying drawings.

This invention has for its object to produce a machine by which rails can be stamped during the process of manufacture with successive numbers or other characters; and it consists 15 of a machine stationed between the finishing-rolls and sawing-machine of a rail-mill, which machine operates in the manner of a steam-hammer, has stamping-dies readily interchangeable during the operation, such stamping dies being automatically dropped upon 20 the rail in advance of the striking-hammer, and being elevated again with such hammer high enough to clear the rail; also, of a vertically-movable anvil actuated by a treadle, 25 to furnish at the proper moment the counterpoise to the blow upon the stamps, the whole being arranged to be under easy control of the operator, all as hereinafter more fully described, and specifically claimed.

30 In the accompanying drawings, Figure 1 represents a side elevation of the machine; Fig. 2, an end elevation of the same; Fig. 3, a longitudinal vertical section of the steam-cylinder, and Fig. 4 a sectional end elevation of 35 such cylinder and valve.

Corresponding letters in the several figures of the drawings designate like parts.

A denotes the standard frame, to be rigidly secured upon a suitable foundation. Against 40 the upper curved end of this frame is bolted the steam-cylinder B, the bore of which, by suitable ports, communicates with the bore of the valve-chest C, that has steam inlet and exhaust port, in the usual manner.

45 The oscillating valve D, having stem d that projects through a stuffing-box, has secured upon its squared end a hand-lever, E, by which such valve is turned in one direction or the other for admitting steam from the boiler into 50 either end of the cylinder.

F is the piston-rod and f the piston, which latter at the end of its upward stroke is cushioned by striking against a pin, a, projected through the cylinder-head b, and having a collar shouldering against the end of a spiral 55 spring, c, that is inserted into a cylindrical extension of head b.

The lower cylinder-cover, g, is arranged with a stuffing-box for forming a steam-tight packing around the piston-rod that passes 60 through it. The flange of this cover g has extensions forming two eyes, h, that are diametrically opposite. The lower end of piston-rod F is inserted into a boss of the oblong hammer-head G, and is secured therein by a 65 key. This hammer-head G has holes j in its ends, that coincide with the eyes h of cylinder-cover g. A downwardly-projecting ridge of the hammer-head forms its striking-face.

The die-holder H is an oblong plate having 70 five (more or less) square holes cut through its center line for the dies i to be inserted, and has holes in its ends, through which the shouldered ends of two rods, J, are inserted and secured by screw-nuts. These rods J are 75 passed vertically through the holes in hammer-head G and eyes h of cylinder-cover g, to be guided therein. Collars K are adjustably secured upon the guide rods J, above hammer-head G, so as to have the die-holder suspended 80 thereon while such hammer-head is on its elevated position. The dies i are square bars of steel that fit easy into the holes of the holder H, and have each a head that receives the blow from the hammer, and prevents the 85 dies from dropping through their holes in the holder. The lower end of each die is tempered after having cut its raised character.

L are two of a series of guide or carrying rollers pivoted between stationary standards. 90 Upon these rollers L the rail travels from the finishing-rolls to the rail-saw, where it is cut proper length, and between two such rollers the machine is placed in a position that the web of the rail will move longitudinally 95 in line with the row of dies i. Under the rail, just vertically below the dies i, is the anvil N, the die of which is shaped to pass between the head and flange of the rail, and to form a uniform supporting-surface for the web of the rail, 100

where the dies *i* will strike it from above. This anvil *N*, however, must not interfere with the moving of the rails over the rollers *L*, and therefore such anvil is arranged to have a vertical motion on or between two guide-stands, *p*, and to be supported on one end of a lever, *m*, at the opposite end of which is formed a treadle, *n*. This lever *m* is pivotally supported at an intermediate point near the anvil 5 in a rigid bracket, *O*, and the anvil is nearly balanced by a counter-weight, *P*, in a manner that, when released, the anvil *N* will be below and entirely clear of the rail, but that by stepping upon treadle *n* such anvil will be raised 10 and pressed under the web of the rail.

Both the lever *E* for operating valve *D* and the treadle *n* are in convenient position to be operated simultaneously by a single man or boy.

During the time the rail is held stationary 15 to be sawed off the proper length, the operator puts his foot upon treadle *n*, to press the anvil under the web of the rail, and then, by swinging the lever *E* upward, he turns the valve *D* 20 to admit steam into the cylinder above the piston, when such piston is forced downward with great velocity. The dies *i* will now land upon the rail first, and then the die-holder will find its resting-place on such rail, whereby the 25 dies are pushed upward in such die-holder, but held securely in proper position on the rail, while the hammer-head *G*, now following, will strike a heavy blow upon such dies, which blow is counterpoised by the anvil *N*.

As soon as the blow has been struck, the operator releases treadle *n*, and swings the lever 30 *E* downward, turning the valve to admit steam under the piston, when the hammer-head is lifted on its upward course, also elevating the dies to clear the rail, which now is forwarded to the cooling-bed. During the interval for stamping the next rail the operator has time 35 to exchange or interchange the dies *i*, sufficient space being provided between the die-holder *H* and hammer-head *G* for removing and inserting dies while such hammer-head is on its elevated position.

What we claim is—

1. In a machine substantially as described,

the combination, with the cylinder and piston- 50 rod carrying the hammer-head, of a die-holder guided by and suspended from such hammer-head, being automatically elevated thereby to clear the rail and provide sufficient space for exchanging dies, as and for the purpose set 55 forth.

2. In a machine substantially as described, the combination, with the cylinder, piston-rod, and hammer-head, of a die-holder having square holes for the reception of headed dies, 60 and being guided by and suspended from such hammer-head, to be automatically elevated for clearing the rail and for providing sufficient space for exchanging dies, as and for the purpose set forth.

3. In a machine substantially as described, the combination, with the cylinder, piston-rod, and hammer-head, of a die-holder supported by guide-rods that are passed through eyes of cylinder and hammer-head, and having adjustable collars for holding suspended such die-holder and hammer-head while on its elevated position, as and for the purpose set forth.

4. The combination, with cylinder *B*, having guide-eyes *h*, and the piston-rod *F*, carrying 75 hammer-head *G* with guide-holes *j*, of die-holder *H*, having guide-rods *J* with collars *K*, all constructed and arranged substantially as described, for the purpose specified.

5. The combination, with cylinder *B*, piston- 80 rod *F*, hammer *G*, and die-holder *H*, and with rollers *L*, of the vertically-movable anvil *N*, actuated by treadle *n*, all substantially as described, for the purpose specified.

6. The combination, with cylinder *B*, rod *F*, 85 hammer *G*, and die-holder *H*, and with rollers *L*, of the vertically-movable anvil *N*, actuated by pivotal lever *m*, having treadle *n* and being counterbalanced by weight *P*, all substantially as and for the purpose described and 90 shown.

In testimony whereof we affix our signatures in presence of two witnesses.

HENRY C. KRIETE.
WILLIAM GILLIES.
